James D. Kay.

Inventor:

William G. Algeo,
by Bakewell, Christy & Kent,
his Atty's.

UNITED STATES PATENT OFFICE.

WILLIAM G. ALGEO, OF ROCHESTER, PENNSYLVANIA.

DESIGN FOR COFFIN END.

Specification forming part of Design No. 5,209, dated August 22, 1871.

To all whom it may concern:

Be it known that I, WILLIAM G. ALGEO, of Rochester, in the county of Beaver and State of Pennsylvania, have invented a new and useful Design for Coffins, Burial-Caskets, &c.; and I do hereby declare the following to be a full, clear, and exact description thereof, reference being had to the accompanying drawing, which represents an inverted end view of a coffin end illustrative of my design.

To enable others skilled in the art to make and use said design, I will proceed to describe the same.

The sides of the coffin are shown at *a* and the top at *b*, with a curved end, as represented. The

coffin end is made up of the pieces *c*, the middle one of which is of a raised rectangular form, as at *d*, and each side piece, on a lower face, has an ogee-molding, by which the edges of such pieces slope off into the sides *a*, to which they are connected.

What I claim as my invention is—

The design for a coffin end, substantially as described and shown.

In testimony whereof I, the said WILLIAM G. ALGEO, have hereunto set my hand.

WILLIAM G. ALGEO.

Witnesses:

W. N. HOWARD,
G. H. CHRISTY.
